UNITED STATES PATENT OFFICE.

WILLIAM A. ZEIDLER AND PAUL M. ZEIDLER, OF NEW YORK, N. Y., ASSIGNEES TO
SOLACE COMFORT SERVICE CORPORATION, A CORPORATION OF NEW YORK.

VENDING-MACHINE.

1,355,583.

Specification of Letters Patent. Patented Oct. 12, 1920.

Application filed October 11, 1919. Serial No. 330,135.

To all whom it may concern:

Be it known that we, WILLIAM A. ZEIDLER and PAUL M. ZEIDLER, citizens of the United States, residing at New York, in the county 5 of New York and the State of New York, have invented a new and useful Improvement in Vending-Machines, of which the following is a specification.

This invention relates to improvement in 10 automatic coin or check controlled vending machines, and it consists of the features of construction and combination of parts hereinafter described and claimed.

The objects of the invention are to correct 15 the defects frequently met with in this class of apparatus, namely: arching or clogging of the articles to be dispensed, interrupting the feed to the ejector, possibilities of illicitly operating the machine and the occasional liability of non-delivery of the article purchased.

Its essential feature of novelty resides in 20 our improved means of insuring feed to the ejector at each operation by agitating the stack in four different directions. Also in 25 our improved means of locking and unlocking the operating mechanism so as to insure proper delivery. These and other features with their functions and operations, are 30 clearly set forth in the accompanying description and drawings, in which—

Figure 1 represents a view of the machine 35 with the front removed, showing the ejector and the agitating mechanism, and the method of locking the coin box in place.

Fig. 2 represents a front elevation of the lower part of the machine, showing the operating handle and the delivery aperture.

Fig. 3 represents an enlarged front view 40 of the ejector with its actuating gears.

Fig. 4 represents an enlarged view of the locking mechanism removed, with the coin slot shown in section.

Fig. 4^a represents an enlarged side elevation of the coin box and its locking mechanism.

Fig. 5 represents an enlarged back view of 50 part of the locking mechanism shown in Fig. 4, with a coin in position, indicated by dotted lines.

Fig. 6 represents an enlarged plan view of the ejector with its operating and locking mechanism, and also represents a similar view of the coin box and its locking mechanism.

Similar symbols of reference refer to similar parts throughout the several views. Referring to the drawings, the numeral 1 indicates a casing or cabinet entirely inclosed, which may be of any size, and formed of any suitable material. The rotating ejector, 2, located preferably at the lower right hand corner of the casing 1, is formed with two pockets or longitudinal slots 2^a—2^a, adapted to remove and deliver the articles or packages from the casing 1. The ejector 2 is also provided with cam shaped projections 2^b—2^b, 2^c—2^c, which act on an oscillating or swinging member 3, hinged to the inner side of top of the casing 1 through rollers, 3^a—3^a, located in depressions, 3^b—3^b, in either side of the member 3, causing it to swing in an arc. A coiled spring, 3^c, located between the inner side of the side wall of the casing and the member 3, serve to keep the rollers 3^a in contact with the cams of the ejector 2 at all times.

Another oscillating member 4 whose normal position is horizontally disposed, is hinged at its inner end to a block, 5, having a curved face 5^a in order to clear the ejector 2; and the lower end of the face of the block 5 is also curved as shown, conforming to the face of the block 6 in order to provide a guide-way from the pocket 2^a of the ejector 2 to the delivery chamber 7. Both the blocks 5 and 6 are screwed or otherwise securely fastened to the bottom of the casing 1 as shown.

It has been shown that the cams, 2^b—2^b, 2^c—2^c act on the rollers, 3^a—3^a, of the swinging member 3, causing it to oscillate. At the lower end of the member 3, an eye 3^d, is provided, into which one end of a rod 8 is pivoted. The lower end of the rod 8 is pivoted to one arm of a bell-crank 9, the other arm of which is in turn pivoted to a rod 10 which is pivoted in an eye 4^a of the member 4. Thus, when the member 3 is swung back and forth in an arc by the cams 2^b—2^b, motion is transmitted through the rod 8, the bell crank 9, and the rod 10 to the member 4, causing it to move upward and downward, and causing the packages 11 indicated by the dotted circles, to roll toward the pockets, 2^a of the ejector 2. The member 4 is cut away at the hinged end forming a portion which extends between the sides of the cams of the ejector 2 as shown. It will be seen that the inner face of the member 3 is provided with

a curved depression 3^a, whose function is to urge the impinging package, 11^a upward and inward as it moves forward. This action, together with the inward and outward movement of the articles or packages by the member 3, and the upward and downward, as well as inward and outward movement of the articles or packages by the member 4, effectually prevents arching or packing, and 10 insures positive feed to the pockets 2^a—2^a of the ejector 2.

In order to rotate the ejector 2, a handle 12 is mounted on a short spindle 13 which passes through the front of the casing; the 15 other end of the spindle 13 being provided with a small pinion 14 which meshes with a gear 15, screwed or otherwise securely fastened to the front end of the ejector 2. It is desired that the ejector make but one-half revolution in order to discharge a single 20 article or package. To this end a rotating toothed member 16, having two pockets, 16^a—16^a in its face, one on each side, diametrically opposed, into which a pawl, 17, 25 actuated by a flat spring 18, rests. The inner side of the member 16 is provided with curved projections, 16^b—16^b, which are held in touch with a back plate 19, by a coil spring 20, set in a pocket 1^a in the front 30 of the casing 1, so that the member 16 is always in yielding contact with the back plate 19. The member 16 is provided with a centrally disposed square hole, 16^c, through which it is mounted on the squared 35 end of a spindle, 21; the spindle 21 being mounted on and pinned to the gear 15, fastened on the end of the ejector 2, and journaled at its other end into a bracket 22, as shown.

40 While the pawl, 17, rests in the pocket, 16^a, the ejector 2 is locked and may only be turned the length of the pocket 16^a. In order to unlock the mechanism and permit the ejector 2 to be rotated, a coin 23 is 45 dropped into the coin slot, 24^a of the member 24, and falls into the position shown in Figs. 4 and 5, resting between one end of a curved projection 16^b, and a lug 16^c, of the member 16. As the pocket 16^a is moved 50 toward the pawl 17, the coin 23 acting as a roller, lifts the pawl from the pocket 16^a, permitting the ejector 2 to be rotated one-half revolution until the pawl 17 drops into the opposite pocket, locking the mechanism. 55 The coin meanwhile has traveled forward until it drops into the chute 25, and thence to the coin box 26.

The coin box 26 is inserted into the bottom 60 of the casing 1 as shown, and is locked into position by means of two members 27—27, one on either side, and hinged to the inside of the bottom of the casing 1. A coiled spring, 28 connects the two hinged members 27—27, which are provided with arms, 65 27^a—27^a, extending forward, embracing a

cam, 29, which is mounted on the spindle of a lock 30, preferably of the Yale cylinder type. The lock 30 being mounted on the face of the casing, 1 as shown. The coin box 26, upon being inserted in place, the 70 rim 26^a of its top is gripped by the members 27—27, holding it firmly in position, and preventing its removal. When it is desired to remove the coin box the lock 30 is turned by its key, not shown, and the cam 75 29 forces the arms 27^a—27^a, apart against the spring 28, disengaging the rim 26^a and releasing the box.

A counter 31 is provided, having an actuating arm 31^a, which is operated by pins, 80 2^c—2^c, on the ejector 2, keeping an accurate account of the operations of the machine.

In operation, a coin is dropped into the coin slot 24^a and the handle 12 turned slightly to the left in order that the coin 85 may fall into its operating position, then moved to the right until the coin, acting as a roller, raises the pawl 17, permitting the ejector 2 to rotate one-half turn, when one article or package is released to fall into the 90 delivery chamber 7.

While the device as illustrated and described is designed to handle cylindrical objects, we do not wish to be restricted to this form alone, as a variety of merchandise may 95 be handled and the form of the machine may be changed without departing from the spirit of the invention.

We claim:

1. In a dispensing apparatus, a revoluble 100 ejector provided with opposed pockets and cams and a chamber, said ejector forming a part of the bottom of said chamber and the cams on said ejector operable to oscillate the remaining floor and a side of said chamber.

2. In a dispensing apparatus, a revoluble 110 ejector comprising a pair of opposed cams with pockets therebetween, a chamber above said ejector, a lever forming a side of said chamber, said lever operable to oscillate by the said cams.

3. In a dispensing apparatus, a revoluble 115 ejector provided with opposed pockets and cams and a chamber, said ejector forming a part of the bottom of said chamber and the cams on said ejector operable to oscillate the remaining floor and a side of said chamber, and a floor to said chamber operable by said lever.

4. In a dispensing apparatus, an ejector 120 comprising a plurality of cams with pockets therebetween and mounted upon a shaft, a coin-operated release for said ejector mounted upon the same shaft.

5. In a dispensing apparatus, an ejector 125 comprising a plurality of cams with pockets therebetween and mounted upon a shaft, a coin-operated release for said ejector mounted upon the same shaft, and means for agi- 130

tating articles above said chamber by the said cams.

6. In a vending machine, an ejector comprising a pair of cams with pockets therebetween and a chamber above said ejector, and means for agitating said chamber by said cams.

7. In a dispensing apparatus, a chamber

provided with a shelf pivotally mounted therein, a lever forming a side of said chamber pivotally mounted from the top of said chamber, a revoluble ejector provided with cams operable to oscillate said lever, said lever operable to oscillate said shelf. 10
